UNITED STATES PATENT OFFICE.

JAMES WRIGHT MACFARLANE AND ANDREW ROBERT ROBERTSON, OF
GLASGOW, SCOTLAND.

CENTRIFUGAL MACHINE.

SPECIFICATION forming part of Letters Patent No. 722,730, dated March 17, 1903.

Application filed February 11, 1902. Serial No. 93,555. (No model.)

To all whom it may concern:

Be it known that we, JAMES WRIGHT MACFARLANE and ANDREW ROBERT ROBERTSON, engineers, of the firm of Watson, Laidlaw and Company, 98 Dundas street, south, in the city of Glasgow, Scotland, have invented certain new and useful Improvements in Centrifugal Machines, of which the following is a specification.

10 This invention relates to improvements in centrifugal machines with reference to an improved valve or cone which closes the discharge-opening of the revolving basket.

In the drawings forming a part of this specification, Figure 1 is a side view of the centrifugal machine, partly in section, with the valve or cone in an open or raised position applied thereto and which is in section. Fig. 2 is a section on the line A B of Fig. 3, and 20 Fig. 3 shows a detail of the valve in a closed position and partly in section.

A conical discharge-valve is free to slide up and down the spindle A and which when fully down serves to close the discharge-opening in the bottom of the centrifugal basket, as shown in dotted lines in Fig. 1. A pin C is fixed to the discharge-valve, fitting into a vertical groove D in the spindle. This pin and groove do not prevent the discharge-valve being raised and lowered, but prevent it turning relatively to the spindle A. A groove or recess, as shown at E, is made in which the pin C may rest, and so support the valve B. A hand-wheel or flange F is fitted to the discharge-valve in such a manner as to allow of its being held by hand and remain motionless while the spindle A and the discharge-valve are revolving. A race of balls, as shown at G', or other form of bearing is fitted between 35 the hand-wheel or flange F and the sleeve of the discharge-valve to reduce the friction as much as possible.

To lift the valve B out of the lower position, as shown by dotted lines, while the centrifugal is in motion, it is only necessary to grasp the hand-wheel and lift the valve. The hand-wheel being very light and of small diameter has very little momentum, and therefore can be easily stopped when grasped by 45 the hand, although the valve itself may continue to revolve with the centrifugal.

To place the valve B in the upper position (shown in full lines) while the centrifugal is in motion, it is necessary to lift it up by the hand-wheel F, so that the pin C is opposite 55 the recess E. Then by slightly retarding the valve B the pin will enter the recess. Conversely, to restore the valve to the dotted position while the centrifugal is in motion it is only necessary to apply the usual brake to the 60 spindle A, so that its motion is slightly checked. The valve B will not be immediately checked, owing to its inertia, but will continue its motion, and the pin C will accordingly pass out of the recess E into a vertical groove D, and by so doing release the valve and permit it to drop.

We likewise construct the upper flange of the discharge-valve in the ordinary "Weston" centrifugal basket covering the opening in 70 the bottom by which the valve is raised or lowered with a loose flange or hand-wheel in the manner already described, so that the valve can be raised or lowered by the hand while the machine is in motion, and that although the part of the valve which is in contact with the machine may revolve the flange or hand-wheel by which the valve is lifted will remain stationary. After the valve has been raised to the required height it is held 80 by a hook or chain attached to the outside framework in the usual way or by any means already well-known in practice.

The reason for being able to lift the discharge-valve while the centrifugal is in motion is that when drying a good quality of sugar the wall of sugar frequently falls down as soon as the centrifugal is stopped, and if the discharge-valve is not raised before that time it becomes buried with the falling sugar, 90 which the attendant has to clear away before he can lift the valve. It will therefore be seen that if the valve be lifted before the machine stops the falling sugar will at once pass through the opening in the bottom of 95 the basket, thereby facilitating the operation of discharging.

What we claim as our invention is—

1. In a centrifugal machine, the combination with the basket having a central opening, and a valve for closing the opening of the basket, of valve-controlling means movable

relatively to the valve and adapted to be gripped by the operator to open the valve.

2. In a centrifugal machine, the combination with the basket having a central opening, of a hand-wheel adapted to move relatively to the valve and to be gripped by the operator to open the valve.

3. In a centrifugal machine, the combination with the basket having a central opening, and a valve for closing the opening, of a hand-wheel to move relatively to the valve, and a ball-race interposed between the valve and the hand-wheel.

4. In a centrifugal machine, the combination with the basket provided with a central opening, and a spindle, provided with a groove, of a valve surrounding the spindle, and a pin carried by the valve holding the valve against rotation relatively to the spindle.

5. In a centrifugal machine, the combination with the spindle provided with a groove and a recess; and a basket, having a central opening, suspended from the spindle; of a valve surrounding the spindle to close the opening of the basket; a pin carried by the valve, and adapted to work in the groove and the recess; a hand-wheel carried by the valve and movable relatively thereto; and a ball-race interposed between the hand-wheel and the valve.

In testimony whereof we affix our signatures in the presence of two witnesses.

JAMES WRIGHT MACFARLANE.
ANDREW ROBERT ROBERTSON.
